SUCKER ROD GUIDE

Tracy S. Park, Houston, Tex., assignor to Gulf Oil Corporation, Pittsburgh, Pa., a corporation of Pennsylvania

Application November 27, 1939, Serial No. 306,399

4 Claims. (Cl. 308—4)

This invention or discovery relates to sucker rod guides; and it comprises a guide for sucker rods in tubing, including a U-bolt, a guide member of such cross section as to loosely fit the tubing, vertically slotted so as to be slipped sideways on the rod, said member having two bores extending therethrough substantially tangent to the rod and arranged to receive the U-bolt, said member further being recessed to receive the U-bolt whereby to protect the U-bolt from rubbing contact with the tubing and nuts engaging the U-bolt ends for drawing the guide member tightly against the rod; all as more fully hereinafter set forth and as claimed.

In oil well pumping, a pump is located near the bottom of the well with a string of tubing extending therefrom up to the surface. The pump is reciprocated from the surface by a string of steel sucker rods threadedly coupled together. The string may be several thousand feet long. The well is rarely perfectly straight or perfectly vertical and as a result the rods tend to rub against the tubing at one or more points. This is disadvantageous not only because of friction losses but also because of liability of breakage. Accordingly it is usual to fit the rods, or some of them, with guides: enlarged members which hold the rods away from the tubing. Because of the extreme shocks and vibrations to which the guides are subjected it has been found very difficult to attach them so they will stay put. Various complicated attachment means have been suggested but such of these as have been tried at all have not proved successful; they loosen in a short time. Probably the most practical form so far developed consists of two half-sleeves screwed together on the rod but even with this form, no matter how tightly the screws are drawn up the guide loosens in a short time. Some proposals have been made in which no attempt is made to fasten the guides rigidly to the rod, the guide sliding freely on the rod between the rod couplings. However such forms not only wear the rod unduly but in using them the fact is disregarded that rod guides serve their function best when firmly attached to the middle of the rod.

One object of the invention is the provision of a rod guide for attachment to the middle or other part of the rod which will stay tight even under extreme vibrating and shock stresses. Other objects include the provision of a rod guide of simple two-piece construction which can be slipped on a rod sideways and drawn up permanently and tightly; the provision of a rod guide

comprising a slotted sleeve and a U-bolt arranged to be drawn tightly against the rod and presenting a flush outer surface without obstructions; and the provision of a guide with U-bolt fastening means in which the fastening means are completely protected from contact with the tubing.

These and other objects are achieved by the provision of a guide including a massive sleeve, generally of cylindrical contour and slotted lengthwise so that it can be slipped on a sucker rod. The sleeve is bored and channeled to receive a U-bolt, the bend of which encircles the rod and the legs of which terminate in flanged recesses in the sleeve. The U-bolt is drawn tight by nuts in the recesses, the arrangement being such that no part of the U-bolt protrudes beyond the sleeve. By virtue of the very small area of contact of the U-bolt with the rod, and the high straining force which can be applied to the nuts, the guide is screwed very tightly to the rod. As a matter of fact it is found in actual practice that the guide, properly applied to the rod, resists dislodgement even under extreme conditions of shocks and vibration. The slot affords free passage for oil, and the smooth exterior of the sleeve affords a minimum of frictional resistance with the tubing.

In the accompanying drawing are shown more or less diagrammatically two examples of specific embodiments of apparatus within the purview of the invention. In the drawing—

Fig. 1 is a view in elevation of one form of the rod guide installed on a sucker rod,

Fig. 2 is a plan view corresponding to Fig. 1,

Fig. 3 is a sectional view taken along line 3—3 of Fig. 1,

Fig. 4 is a sectional view taken along line 4—4 of Fig. 3, and

Fig. 5 is a view in elevation of a modified form of guide.

Referring to the drawing and more particularly to Figs. 1 to 4, the guide is shown installed on a pump sucker rod 10 of ordinary circular cross-section, operating in a well tubing 11. The guide includes a sleeve member 12 of rather massive, symmetrical construction, the body portion 13 of which is cylindrical with two frustoconical ends 14 and 15. The sleeve member has a U-shaped slot with walls 16 and 17 slightly flaring outwardly as shown and a circular bottom 18 corresponding closely to the rod diameter so that the sleeve can be slipped on the rod sideways. The edges of the slot are rounded at 19. The sleeve member has two channels or grooves 20

and 21 in the faces of walls 18 and 17, arranged for reception of a U-bolt 22, the ends of which protrude through bores 23 and 24 in the sleeve member, these bores being prolongations of the channels. The sleeve member is cylindrically recessed at 25 and 26 for reception of nuts 27 on the ends of the U-bolt. Lock washers 28 are interposed between the nuts and flange portions 29 and 30 of the sleeve. Recesses 25 and 26 are deep enough so that the nuts and the U-bolt ends lie below the surface of the sleeve member and are effectively protected against contact with the tubing. Recesses 25 and 26 are also large enough to admit a socket wrench for tightening the nuts. The inner circular portion of the U-bolt is advantageously flattened as shown in Figs. 3 and 4, so as to avoid excessive localized strains.

To install the guide, the sleeve member is applied to the rod and the U-bolt inserted and drawn up tightly. By virtue of the small contact area of the U-bolt, the contact pressure is very high and dislodgement of the guide is obviated. But should the guide become loosened for any reason, as by failure of the U-bolt, by virtue of its shape it cannot come off the rod and fall down the well; nor can it jam the rod by cocking or wedging sideways. The U-bolt is under tension load only; the guide member is under compression load only.

Fig. 5 shows a modification of the apparatus, adapted for use in wells which tend to deposit paraffin on the tubing walls. The sleeve member 112 is made like that of Fig. 1 except that in lieu of providing an upper tapered portion, the body member 13 terminates in a sharp-edged flat face 39 the edge of which scrapes paraffin on the up-stroke.

The sleeve member is advantageously embodied in steel or bronze and may be a casting, or a turning, or a turned casting. If made of bronze or other metal dissimilar to the metal of the rods it is best to provide a coating of asphaltic paint or other insulation (not shown) between the guide and the rod, to prevent electrolytic corrosion. The U-bolt and nuts are best made of high-tensile steel.

The guide has been described in connection with round sucker rods, the ordinary form. The guide is of course equally well adapted for application to rods of other cross-sections.

What I claim is:

1. A guide for sucker rods in tubing and adapted for rigid attachment to a rod at a point

intermediate the ends thereof, comprising a U-bolt encircling one side of the rod and flattened on the inside of the bend thereof, a detachable guide member partly encircling the rod and bored to receive the U-bolt legs, and separate nuts engaging each U-bolt leg for drawing the U-bolt tightly against the rod, the guide member being constructed and arranged to project radially beyond the U-bolt legs and nuts to protect the U-bolt from rubbing contact with the tubing.

2. A guide for sucker rods in tubing comprising in combination a sleeve guide member vertically slotted to receive a sucker rod in substantially symmetrical relation thereto and recessed on the side opposite the slot, a U-shaped clamping member inset in the sleeve member, engaging the exposed side of the rod and terminating within the recessed sleeve member, and separate clamping means lying wholly within the recessed sleeve member and engaging the legs of the U-shaped clamping member, for straining the U-shaped clamping member against the rod.

3. A sucker rod guide comprising a substantially cylindrical body member having a vertical radial slot in one side thereof extending from the periphery past the central axis of the body member so as to permit placing the body member symmetrically on the rod, the body member having two bores extending transversely therethrough, a U-shaped bolt having a flattened bend portion engaging the rod over a substantial area for frictional engagement with the rod, the legs of the bolt extending through the bores and terminating below the periphery of the body member, and threaded clamping means disposed below the periphery of the body member and firmly engaging the legs of the bolt.

4. A guide for sucker rods in tubing comprising a thick metal guiding sleeve member of horizontal cross-section smaller than the tubing and provided with a vertical rod-receiving slot, whereby the sleeve member is adapted to be slipped sideways on a rod, bores in the sleeve member tangential to the rod, a U-bolt surrounding the rod, the legs of the U-bolt extending through said bores and terminating short of the outer periphery of the sleeve member on the side of the sleeve member opposite the slot, and separate clamping nuts on each of the legs, inset below the outer periphery of the sleeve member, for straining the sleeve member tightly against the rod.
